(57) **CLAIM**

The ornamental design for a barbecue grill, as shown and described.

DESCRIPTION

FIG. 1 is a front left perspective view of a barbecue grill, in a closed configuration, according to the present invention.

FIG. 2 is a front view of the grill shown in FIG. 1.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a front left perspective view of the barbecue grill shown in FIGS. 1-7, in an open configuration.

FIG. 9 is a left side view of the grill as shown in FIG. 8.

FIG. 10 is a right side view thereof.

FIG. 11 is a front view thereof.

FIG. 12 is a rear view thereof.

FIG. 13 is a top view thereof.

FIG. 14 is a bottom view thereof; and,

FIG. 15 is a top detail view of a portion of the grill shown in FIG. 8, in an open configuration.

The broken lines depict portions of the barbecue grill that form no part of the claimed design.
